JAMES W. PACKARD, OF BROOKLYN, NEW YORK, ASSIGNOR OF ONE-HALF
TO NORMAN HUBBARD, OF SAME PLACE.

VACUUM-PUMP.

SPECIFICATION forming part of Letters Patent No. 406,110, dated July 2, 1889.

Application filed September 28, 1887. Serial No. 250,902. (No model.)

To all whom it may concern:

Be it known that I, JAMES W. PACKARD, of Brooklyn, in the county of Kings and State of New York, have invented a new and Improved Vacuum-Pump, of which the following is a full, clear, and exact description.

The invention consists of the construction, arrangement, and combination of parts, all as hereinafter described and claimed.

10 Reference is to be had to the accompanying drawing, forming a part of this specification, in which the figure is a longitudinal sectional elevation of a pump made in accordance with my invention.

15 The piston-rod A is made hollow for a portion of its length and the passage *a* therein is made in two diameters, the same being somewhat enlarged at *a'*, at and near the inner end of the piston-rod.

20 In the passage *a* is fitted the small rod B, which operates the valve C at the induction end of the pump. The rod B is connected to the valve C by a ball-and-socket joint, and is split at its upper end to form spring-tongues,

25 which act as friction-surfaces in the passage *a*, so that the rod will be raised by the lifting of the piston until the ends of the springs reach the enlargement *a'*, when the rod will be released and permit the valve C to close 30 of its own weight. The seat for the valve C is formed in the T-coupling D, and it is held to a very limited movement by the pin *d*, passed through a slot *d'*, formed in the extension *d''* at the bottom of the valve.

35 The branch D' of the coupling D serves to connect the pump with the vessel to be exhausted. The lower branch D'' projects below the branch D', and is closed with a screw-cap B³ and constitutes a trap to catch any 40 moisture that may condense in the pump, and which may be removed by removing the cap D³.

45 The upper end of the valve C is formed with a small projection *c*, which is screw-threaded upon its outer surface and formed with a cup or socket *c'* at the top to receive the ball *b* of the rod B. This ball is held in the cup or socket *c'* by the cap-plate *f*, placed upon the rod and screwed upon projection *c*, 50 thus forming a very cheap and very practical ball-and-socket connection of the rod B

with the valve C, which obviates all binding of the rod and gives the valve C perfect freedom of action.

The great advantage of the construction involving a universal joint between the valve and the valve-stem, as shown in my ball-and-socket joint, is that the valve is left free to seat itself perfectly, unaffected by any buckling or warping of the valve-stem. Moreover, should the valve-stem be broken in the rapid operation of the pump it can be removed and replaced at slight cost and without the necessity of putting in a new valve, which would have to be ground to a seat in the usual tedious and costly manner.

In the piston-head E is fitted the valve F, which projects below the piston-head, and is lifted when it nears the limit of the piston-stroke by contact of the valve with the lower 70 cylinder-head G.

In the upper cylinder-head H is formed an opening *h*, through which projects the exhaust-check valve J, so that the said valve will be opened by the piston-head striking 75 the lower end of the valve. This valve is shown open in the drawings. As the piston-head starts downward, the valve will close of its own weight and prevent the admission of air to the pump-cylinder. The valve J is held in 80 a separate casing K, formed with a flange *e*, through which are passed the fastening-screws *e'* for securing the casing and inclosed valve to the head-plate H in position over the aperture *h* in the said head-plate. The bottom of the 85 casing K is formed with the valve-seat *h'*, which coincides with the aperture *h*, as shown clearly in the drawings. The top of the casing K is closed by a screw-plug *k*, which is formed with a central cavity *k'* to receive and 90 guide the stem *j* of the valve J, so that all lateral movement or displacement of the valve is obviated.

The great advantage and necessity of having the valve in the piston positively operated in order that a high vacuum may be produced depends on the fact that this valve is to be opened at the moment when the rapidly-reciprocating piston is reversing its motion. Consequently the momentum of the 100 valve (a by no means insignificant force) tends to keep it closed and the tension of the small

quantity of air entrapped within the cylinder when a nearly complete vacuum has been produced in the receiver is insufficient to lift the valve from its seat in opposition to the combined influence of its weight and momentum, so that it must be positively operated in the manner which I have described, or its equivalent.

Having thus described my invention, what I claim as new, and desire to secure by Letters Patent, is—

1. In a mechanical air-pump, the combination of the cylinder, the piston, the valve in the piston, and the projecting valve-stem, which strikes the cylinder-head as the piston approaches one extremity of its travel, substantially as described.
2. In a mechanical air-pump, the combination of the cylinder, the piston, the positively-operated induction-valve at one end of the cylinder, the valve in the piston, together with its projecting valve-stem, which strikes the cylinder-head, and the eduction-valve at the other end of the cylinder, together with its projecting valve-stem, which is struck by the piston, substantially as described.

3. In a mechanical air-pump, the combination of the cylinder, the piston with its hollow piston-rod bored to different diameters at different points in its length, the valve in the cylinder-head, the valve-stem, which extends into the hollow piston-rod and has frictional contact therewith, and the universal joint between said valve-stem and valve, whereby said valve is positively operated in both directions, substantially as described.

4. In a mechanical air-pump, the combination of the cylinder, the piston with its hollow piston-rod, the valve in the cylinder-head, the valve-stem, which extends into the hollow piston-rod and has frictional contact therewith by means of the split and expanded end of said valve-stem, and the universal joint between said valve-stem and valve, substantially as described.

JAMES W. PACKARD.
